The ornamental design for a workbench, as shown and described.

DESCRIPTION

FIG. 1 is a perspective view of an embodiment of a workbench.

FIG. 2 is a front elevational view of the workbench of FIG. 1. FIG. 3 is rear elevational view of the workbench of FIG. 1. FIG. 4 is a right side elevational view of the workbench of FIG. 1.

FIG. 5 is a left side elevational view of the workbench of FIG. 1.

FIG. 6 is top plan view of the workbench of FIG. 1.

FIG. 7 is a bottom plan view of the workbench of FIG. 1.

FIG. 8 is a perspective view of the embodiment of the workbench in FIG. 1 with the power strip and cord shown in dot-dot broken lines.

FIG. 9 is a front elevational view of the workbench of FIG. 8.

FIG. 10 is rear elevational view of the workbench of FIG. 8.

FIG. 11 is a right side elevational view of the workbench of FIG. 8.

FIG. 12 is a left side elevational view of the workbench of FIG. 8.

FIG. 13 is top plan view of the workbench of FIG. 8.

FIG. 14 is a bottom plan view of the workbench of FIG. 8.

FIG. 15 is a perspective view of another embodiment of the workbench.

FIG. 16 is a front elevational view of the workbench of FIG. 15.

FIG. 17 is rear elevational view of the workbench of FIG. 15. FIG. 18 is a right side elevational view of the workbench of FIG. 15.

FIG. 19 is a left side elevational view of the workbench of FIG. 15.

FIG. 20 is top plan view of the workbench of FIG. 15.

FIG. 21 is a bottom plan view of the workbench of FIG. 15.

FIG. 22 is a perspective view of yet another embodiment of the workbench.

FIG. 23 is a front elevational view of the workbench of FIG. 22.

FIG. 24 is rear elevational view of the workbench of FIG. 22.

FIG. 25 is a right side elevational view of the workbench of FIG. 22.

FIG. 26 is a left side elevational view of the workbench of FIG. 22.

FIG. 27 is top plan view of the workbench of FIG. 22; and,

FIG. 28 is a bottom plan view of the workbench of FIG. 22. The dot-dot broken lines shown are included for the purpose of illustrating portions of the workbench that form no part of the claimed design.
